UNITED STATES PATENT OFFICE.

JOHN T. GREENWOOD, OF KALAMAZOO, MICHIGAN.

CULTIVATOR.

SPECIFICATION forming part of Letters Patent No. 425,030, dated April 8, 1890.

Application filed September 13, 1889. Serial No. 323,801. (No model.)

To all whom it may concern:

Be it known that I, JOHN T. GREENWOOD, a citizen of the United States, residing at Kalamazoo, county of Kalamazoo, State of Michigan, have invented a new and useful Improvement in Cultivators, of which the following is a specification.

This invention has for its object the construction of a cultivator-share standard, a share, and a brace to said standard, said three elements being made out of a single bar of metal.

Other objects will appear in the following description and claims.

15 In the drawings forming a part of this specification, Figure 1 is a side elevation, Fig. 2, same showing a change; and Fig. 3 is a sectional elevation on a vertical line near the bolt X in Fig. 2.

20 Referring to the lettered parts of the drawings, B will serve to illustrate a beam of a cultivator-frame. The standard, including the front bar D, the horizontal part E, which is bolted to the frame, and the downwardly-oblique brace C, somewhat resembles a triangle.

25 In Fig. 1 the front bar D of the standard terminates in a share at the lower end and the lower end of the brace C terminates just above said share end, at which point the end 30 of the brace is bolted to the front bar by a bolt x, passed through the hole c. The bolt x is not shown in Fig. 1, but appears in Fig. 3.

Figs. 2 and 3 show how other styles of shares may be attached to the standard by the same bolt x to adapt it for different uses. As in 35 Fig. 2, the share is suitable for cultivating, while in Fig. 1 it is more especially adapted for harrowing. This harrow-tooth can be made very cheaply, is strong, simple, and well braced.

If preferred, the bolt x may be dispensed with, as in Fig. 1, and the brace merely rest against the front bar D.

Having thus described my invention, what I claim as new, and desire to secure by Letters 45 Patent of the United States, is—

1. The share-standard comprising the front bar, the upper horizontal part, and the brace, the lower end of the front bar being provided with a share or working-point, said part being formed from a single bar of metal, substantially as set forth.

2. The triangular-shaped share-standard, in combination with a detachable share or working-point, substantially as set forth.

In testimony of the foregoing I have hereunto subscribed my name in presence of two witnesses.

JOHN T. GREENWOOD.
